UNITED STATES PATENT OFFICE

EARL B. WAGONER, OF LAKWOOD, OHIO, ASSIGNOR TO THE STANDARD OIL COMPANY,
OF CLEVELAND, OHIO, A CORPORATION OF OHIO

DESIGN FOR A SERVICE-STATION BUILDING

Application filed November 11, 1931. Serial No. 41,694. Term of patent 14 years.

To all whom it may concern:

Be it known that I, EARL B. WAGONER, a citizen of the United States, and a resident of Lakewood, county of Cuyahoga, and State of Ohio, have invented a new, original, and ornamental Design for Service-Station Buildings, of which the following is a specification, reference being had to the accompanying drawings, forming a part thereof.

In said annexed drawings:

Fig. 1 is a perspective view; and Fig. 2 is a plan view of my design.

As indicated, the design presents a somewhat paneled aspect, and provides convenient doors and windows. The other side of the building is on similar general lines.

I claim:

The ornamental design for a service-station building as shown and described.

Signed by me this 4th day of November, 1931.

EARL B. WAGONER.
